United States Patent Office

Des. 202,389
Patented Sept. 21, 1965

202,389

TYPESETTING MACHINE

Viktor Schreckengost, Cleveland, Ohio, assignor to Harris-Intertype Corporation, Cleveland, Ohio, a corporation of Delaware

Filed May 12, 1964, Ser. No. 79,937

Term of patent 14 years

(Cl. D64—11)

FIG-1

FIG-2

FIG-3

FIG-4

FIG. 1 is a perspective view of a typesetting machine, showing my new design;

FIG. 2 is a perspective view showing the rear of the machine shown in FIG. 1, as well as the left side of the machine as shown in FIG. 1;

FIG. 3 is a plan view of the machine shown in FIG. 1; and

FIG. 4 is a side elevation thereof.

I claim:

The ornamental design for a typesetting machine, as shown.
